ELEVATOR CONTROL SYSTEM

Joseph H. Borden, Toledo, Ohio, assignor to
 Haughton Elevator Company, Toledo, Ohio, a
 corporation of Ohio

Application February 27, 1952, Serial No. 273,593

10 Claims. (Cl. 187—29)

1

This invention relates to control systems for freight and passenger elevators and in particular to simplified controls for maintaining floor finding devices and speed controlling equipment in proper operational synchronism with an elevator car moving in a hatchway.

It has been common practice to drive a floor selecting device for an elevator by means of tapes or cables that are attached to the elevator car and that are wound onto and attached to a drum or pulley geared to the selecting device. These tapes or cables are in addition to the cables that support the elevator car. Attempts have been made to eliminate the tape or cable drive for the floor selector and to drive the selector directly from the elevator drive motor. Such a control drive, when used with a traction drive, must make provision for the creepage that occurs between the elevator support cable and the motor drive pulley as the cable runs over the drive pulley. Such creepage, if not corrected, causes serious errors in the position of the floor selecting device mechanism. Complicated and expensive correcting devices have been employed to correct this creepage of the cables.

The principal object of this invention is to provide an improved creepage compensating mechanism that is simple, inexpensive and thoroughly reliable.

Another object is to provide a clutch mechanism in the drive between an elevator drive motor and a cooperating floor selecting or other control mechanism to cooperate with means operatively connected to the floor selecting mechanism and adapted to slip the clutch mechanism when the car is leveled at a floor to synchronize the floor selecting mechanism with the elevator car and thus correct for creepage of the drive cables.

A still further object of the invention is to adapt an improved creepage correcting mechanism to an elevator control system employing a small constant speed reversible motor for driving a part of the floor selecting mechanism.

A still further object is to provide an electrically controlled clutch in the drive mechanism for an elevator control mechanism to cooperate with mechanical centering devices arranged so that when the clutch is released with the car level with a floor the centering devices accurately position the floor selecting mechanism and thus correct for any accumulating creepage error.

More specific objects and advantages will be apparent from the following description of several embodiments of the invention.

According to the invention a slippable clutch is

2

included between a drive shaft of a traction type elevator drive motor and a floor selecting and controlling equipment and correcting means are provided for slipping the clutch in the event that the elevator car is level at a floor and the control mechanism has not assumed a precisely corresponding position. A traction type elevator is one in which the supporting cables for the car are carried over and frictionally driven by a drive pulley on the elevator drive motor shaft and then down the side of the hatchway to a counterweight, the friction between the cables and the drive pulley being relied upon to transmit power from the drive pulley to the car. The slippable clutch may be either a spring loaded or magnetically actuated friction clutch adapted to slip in case of overload or upon release of the actuating means. The correcting means, which is energized only when the elevator motor is stopped with the car at a floor, is adapted to slip the clutch by the driving effort of an auxiliary motor or to release the clutch and permit a mechanical centering device or a detent to move the selecting mechanism into its proper position.

In normal operation of an elevator the support cable tends to creep one way or the other with respect to the elevator drive pulley depending upon the amount of load and direction of travel of the elevator. The amount of creepage is not large but must not be allowed to accumulate. Therefore, except under unusual emergency situations, it is not necessary to make large corrections.

The improved correcting devices may be substituted for more complicated arrangements such as are shown in United States Patent No. 1,943,114, issued January 9, 1934, or No. 2,062,432, issued December 1, 1936.

Improved correcting devices employing the invention are illustrated in the accompanying drawings. In the drawings:

Figure I is a schematic representation of an elevator control system employing one form of the invention.

Figure II is a similar schematic figure employing a second form of the invention.

Figure III is an enlarged schematic illustration of an electrically actuated clutch used in the embodiment shown in Figure II.

Figures IV and V are simplified illustrations of a restoring or centering mechanism that cooperates with the electrically actuated clutch to center the control mechanism illustrated in Figure II.

Figure VI is a partially broken away side elevational view of a contacting mechanism serv-

55

ing as a rheostat control for the elevator drive motor.

Figure VII is a partially broken away plan view of the contacting mechanism.

Figure VIII is a vertical section of the contacting mechanism as seen from the line VIII—VIII of Figure VII.

Figure IX is a simplified wiring diagram showing only enough of the control system to explain the operation of the creepage correcting mechanism.

Figure X is a similar wiring diagram as modified to cooperate with the correcting mechanism shown in Figure II.

Figure XI is a simplified schematic illustration of another embodiment of the invention.

Figure XII is a simplified wiring diagram to show the electrical control for mechanism shown in Figure XI.

These specific figures and the accompanying description are merely to illustrate the invention and not to limit its scope.

In the simplified elevator control system shown in Figure I, an elevator car 1 is supported by a cable 2 trained over a drive pulley 3 and attached to a counterweight 4. The drive pulley 3 is mounted on an armature shaft 5 of a slow-speed direct-current elevator motor 6. A brake assembly 7 mounted adjacent the motor 6 is released when the motor is energized and is spring set when the motor is de-energized to prevent coasting of the elevator car 1.

The elevator motor 6 is controlled according to signals transmitted from a floor selector mechanism 8 and a speed control rheostat assembly 9. The signals to initiate the starting and stopping of the drive motor 6 originate from the floor selector mechanism 8 as the operator or passengers register their calls, while the acceleration, deceleration, and constant speed running of the motor 6 is controlled by the rheostat 9.

In the control system illustrated in Figure I the floor selector mechanism 8 includes a carriage 10 that is supported and driven past banks of fixed contacts 11, each represented by a single contact, by a chain drive 12. The chain 12 is driven by a shaft 13, gearing 14 and a shaft 15 connected to a reversible constant speed advance motor 16. The advance motor 16 is preferably a slow-speed synchronous inductor motor having a full speed of approximately 75 revolutions per minute. This type of motor, which is manufactured by the General Electric Company, is characterized by its extremely rapid acceleration and deceleration. The motor 16, which is driven by alternating current, reaches full speed within one cycle of the alternating current from the time it is energized and stops just as quickly when it is de-energized. The gear ratio through the gearing 14 and the chain drive 12 to the carriage 10 is such that the carriage 10 moves from one bank of contacts 11 to the next in the same time that the elevator car moves from one floor to the next when traveling at its normal running speed.

Conventional circuits such as are shown in the patents referred to are employed to energize the advance motor 16 when it is desired to operate the elevator from one floor to another. In addition, the floor selector mechanism 8 includes a contact arrangement that continues to energize the advance motor 16 in one direction or the other until the carriage 10 is accurately centered with respect to the bank of contacts 11 representing the floor at which the car is to be stopped.

The acceleration, running speed and deceleration of the elevator drive motor 6 is controlled by the rheostat assembly 9. The rheostat 9, driven through a differential gear assembly 17, 5 is jointly under the control of the advance motor 16 and the elevator drive motor 6. The advance motor 16 tends to drive the rheostat 9 in a direction to accelerate the elevator motor 6 in a direction to follow the advance motor 16. Simultaneously the elevator motor 6, as it follows the advance motor 16, tends to drive the rheostat 9 in a direction tending to reduce the speed of the elevator motor 6. When the speeds correspond the rheostat stops.

10 The differential gear assembly 17 comprises a first input element or gear 18 connected to the shaft 15 driven by the advance motor 16, a second input gear 19 carried on a shaft 20 which is connected through friction clutch 21 to the armature shaft 5 of the elevator drive motor 6, a carrier 22 including gears 23 and 24 meshing with the input gears 18 and 19, and a carrier supported output gear 25 which through an idler 26 drives a gear 27 fixed on a shaft 28 of the 25 rheostat assembly 9.

In this arrangement, the advance motor 16 operating in response to floor selector control circuits drives the floor selector carriage 10 towards the selected floor and at the same time, through 30 the differential gear mechanism 17 turns the rheostat shaft 28 in a direction to start and accelerate the elevator motor 6. The rheostat continues to turn until the speed of the shaft 28 connected to the elevator drive motor 6 corresponds to and is opposite in direction to the speed of the advance motor shaft 15. When these 35 speeds become equal the differential carrier 22 and the rheostat stops and the elevator drive motor runs at constant speed. At this time the 40 elevator car 1 lags behind a position corresponding to the position of the floor selector carriage 10 by an amount determined by the gear ratio and the movement of the rheostat 9 required to bring the elevator motor 6 up to speed. This lag is made generally proportional to the operating 45 speed of the elevator and may be as great as twenty feet for an elevator operating at 800 feet per minute.

When the floor selector carrier 10 reaches the 50 bank of contacts 11 corresponding to the floor at which a stop is to be made the advance motor 16 is de-energized, instantly stops, and thereafter maintains the floor selector mechanism in a position corresponding to that floor. At this instant 55 of stopping of the advance motor 16 the elevator car 1 may be as much as two floors away from the floor at which it is to stop and is moving at full speed. The stoppage of the advance motor 16 stops the input gear 18 of the differential assembly 17 so that the elevator drive motor 6, driving through the second input gear 19, rotates the differential carrier 22 and with it the rheostat 9 toward the slow or zero speed setting. As the 60 rheostat returns toward its center or zero speed setting the speed of the elevator drive motor 6 is correspondingly reduced. As the car approaches within a few feet of the floor at which it is to stop, leveling switches, mounted on the car and cooperating with inductor plates or cams 65 in the hatchway, signal the exact position of the car and take over the control of the elevator motor 6 so as to bring the car 1 to a stop level with the floor regardless of any creepage that may have occurred between the support cable 2 and the pulley 3 or any stretch in the cable 2 because 70 75

of load in the elevator car 1. If it should happen because of creepage or stretch that the rheostat 9 does not return precisely to zero when the car is level at a floor auxiliary control circuits including a rotating contact arm 29 on the rheostat shaft 23 cooperating with fixed contacts 30 or 31 energize a correction motor 32 which through gearing 33 is connected to the input shaft 20 intermediate the clutch 21 and the second input gear 18 of the differential. The motor 32, energized through one or the other of the contacts 30 or 31, develops sufficient torque to slip the clutch 21 and to drive the shaft 20 in a direction to return the rheostat assembly 9 to its center position. The required slipping of the clutch 21 corresponds to and corrects for the creepage and stretch of the cable 2 and thus maintains synchronism between the car position and the control mechanism position.

Figure II schematically illustrates another embodiment of the invention. In this embodiment mechanical means are employed for synchronizing the rheostat. As illustrated in Figure II an elevator car 34 is supported and driven by a cable 35 running over a grooved pulley 36 and connected to a counterweight 37. The pulley 36 is mounted on an armature shaft 38 of a slow-speed direct-current elevator drive motor 39. A spring-set, electrically-released brake mechanism 40 operatively attached to the armature shaft 38 holds the armature shaft against rotation when the drive motor 39 is de-energized. As in the preceding example, an advance motor 41 is connected through gearing 42 and a chain drive 43 to move a floor selector carriage 44 past a plurality of banks of contacts 45, each of which banks is represented by a single contact, corresponding to the floors served by the elevator car 34.

The speed of the elevator drive motor 39 is controlled by a rheostat assembly 46 including a moving arm 47 that is mounted on and driven by a shaft 48 operatively connected through an electrically actuated clutch 49 and gearing 50 to an output gear 51 of a differential gear mechanism 52. The differential gear mechanism 52 comprises a carrier 53 that is directly connected to the output gear 51, a pair of differential gears 54 and 55 mounted in the carrier 53, a first input gear 56 operatively connected to the armature shaft 38 of the drive motor, and a second input gear 57 operatively connected through a shaft 58 to the advance motor 41.

In Figures I and II the control mechanism is shown schematically and while the differential gear mechanism is shown as connected directly on the shafts of the elevator motors and advance motors it is to be understood that in actual construction gearing or other mechanical drive means may be interposed between the motor and the differential gear mechanism and that other forms of differential gear mechanism may be substituted for the bevel gear differential schematically illustrated in the figures.

In this example, as in the first, the advance motor 41 is preferably a constant-speed reversible motor having very rapid acceleration and deceleration characteristics. When it is desired to operate the elevator car 34 from one floor to another the advance motor 41 is suitably energized and it immediately drives the selector carriage 44 at constant speed towards that bank of contacts 45 which represents the selected floor at which the car is to stop. As the advance motor 41 is driving the selector carriage 44 it also, through the differential gear mechanism 52 and the now

energized clutch 49, rotates the arm 47 of the rheostat assembly 46 so as to start and accelerate the elevator drive motor 39. As the elevator motor 39 accelerates it turns the connected differential input gear 56 oppositely to the advance motor driven input gear 57 to reduce the speed and finally stop the motion of differential carrier 52 and the rheostat arm 47. The rheostat arm 47 stops at a position such that the elevator motor 39 operates under the then applied load at its normal full speed. Any tendency of the elevator motor to run faster or slower results in movement of the differential carrier 52 and rheostat arm 47 in a direction to correct the motor speed.

Because of the differential action and the movement required in the rheostat assembly 46 the elevator car 34 lags behind a position corresponding to the position of the selector mechanism carriage 44. When the selector mechanism carriage 20 reaches that one of the banks of contacts 45 representing the selected floor the advance motor 41 is immediately stopped thereby stopping the input gear 57 of the differential mechanism 52. The continuing rotation of the elevator drive motor 39 then drives the differential gear mechanism 52 and the rheostat arm 47 back to its center position thereby decelerating the elevator motor 39 as the rheostat approaches its zero speed position. As in the preceding example leveling switches (not shown) on the car 34 and actuators in the hatchway control the final movement of the elevator drive motor 39 to stop the car 34 level with the selected floor. If there is no stretching of the cable 35 or creepage with respect to the pulley 36 the rheostat arm 47 returns to its center position as the car is leveled with a floor.

While the actual position of the differential carrier 53 is immaterial, it is necessary that the rheostat arm 47 be accurately returned to its center position each time the car 34 is leveled with a floor. In this embodiment the electrically actuated clutch 49 is released whenever the elevator car 39 stops and the leveling switches indicate that the car is level with the floor. As soon as the clutch 49 releases, a gravity operated centering mechanism 58 immediately returns the rheostat arm 47 and shaft 48 to their center positions. A simple mechanical return mechanism for this purpose comprises a pair of arms 60 and 61 that are loosely journaled on and that extend radially in a downwardly inclined direction from the shaft 48. The arms 60 and 61 carry weights 62 and 63 on their lower ends. A driving member or collar 64 fixedly mounted on the shaft 48 has laterally extending lugs 65 and 66 which selectively engage the arms 60 and 61 depending upon the direction of rotation so as to lift the engaged arm and its weight away from a stop 67. When the clutch releases, the elevated one of the weighted arms 60 or 61 returns the shaft 48 to its centered position. In this embodiment the release of the electrically actuated clutch 49 and the mechanical centering action of the weighted arms 60 and 61 serves the same purpose as does the correction motor 32 and the friction clutch 34 shown in Figure I. In each example a clutch is included in one of the connections to the differential gear mechanism. In each embodiment the clutch is slipped each time the elevator car is leveled at a floor in an amount that compensates for the creepage that may have occurred between the elevator drive motor pulley and the car supporting cable.

In order to protect the control mechanism in-

cluding the rheostat assembly 9 or 46 from damage the clutches 21 or 49 are constructed to have limited torque transmitting capacity so that they may slip before sufficient torque is transmitted to the rheostat or floor selecting mechanism to cause damage. In the embodiment shown in Figure I the torque transmitting capacity of the clutch 21 must be low enough so that the correction motor 32 can slip the clutch. In the embodiment shown in Figure II, the electrically actuated clutch (shown also in Figure III) comprises a magnet member 68 having a coil 69 arranged to attract an armature disk 70 with only sufficient force to reliably transmit the torque required to lift the engaged one of the weighted arms 60 or 61 and to operate the rheostat arm 47. Should the rheostat jam with the elevator motor or the advance motor running the clutch slips before any parts are damaged. This just described slipping, which may occur at any time, is a safety precaution only and has nothing to do with the slip, occurring when the car is stopped at a floor, that corrects for creepage of the cables.

One of the problems involved in any elevator installation is to design the equipment for long life and simple maintenance. Since the rheostat assembly 9 or 46 as illustrated in Figures I and II is operated from center to nearly its complete range of movement in one direction or the other for every start and stop of the elevator the ordinary sliding contact rheostat such as is ordinarily used in the control of the direct current motors has too short a life to be satisfactory. According to this invention the rheostat assembly is constructed, as illustrated in Figures VI, VII and VIII, by substituting a plurality of cam operated switches for the usual sliding contacts. The cam operated switches short out various sections of a field control resistor employed with a generator driving the elevator motor. The improved rheostat assembly comprises a box-like frame having a continuous bottom plate 71 and integrally formed upright end portions 72 and 73. The end portions 72 and 73 are connected together and braced by two pairs of longitudinally extending threaded rods 74, 75 and 76, 77. The threaded rods are located along the sides of the assembly so as to leave a large free central space in the frame. A plurality of shallow U-shaped subframes 78 are mounted on the threaded rods with the flat bottom portion of each U-shaped frame extending parallel to and spaced from a plane through the pair of rods supporting that subframe. The flat bottom portion of the U-shape of the subframe 78 comprises a small panel 79 of insulating material on which is mounted a plurality of pairs of stationary contact buttons 80. Each pair of contact buttons 80 are bridged by a movable contact bar 81 resiliently mounted on the end of an arm 82 pivotally mounted on an axle 83 carried in the subframe 78. A helical compression spring 84 compressed between the arm 82 and the insulating panel 79 urges the arm away from the panel in order to separate the contact bar 81 from the contacts 80. Each of the arms 82 has a downwardly extending portion 85 carrying a roller 86 which cooperates with a cam 87 adjustably mounted on a shaft 88 journaled in the end frame portions 72 and 73. The shaft 88 functionally corresponds to the shafts 28 and 48 of Figures I and II respectively.

Suitable gearing, such as gears 89, 90 and a chain sprocket 91 may be mounted on the end frame 73 and employed to connect the shaft 88

to the differential mechanism. As indicated in Figure II the electrically actuated clutch 49, if used, is included between the shaft operating the contacts (the shaft 88) and the gearing such as the gears 89 and 90.

For convenience in wiring, the fixed contacts 80 each having a terminal stud 92 extending inwardly into a wiring space between the subframes 78 and above the path of the cams 87 on the shaft 88. A cover 93 fitting over the assembly of subframes 78 and the end frames 72 and 73 is attached to longitudinally extending angle irons bolted to the base 71.

In this preferred rheostat assembly the contacts 80 and contact bar 81 are used to short out resistors or sections of a resistor assembly in the motor speed control circuits. Some of the contacts may be used for other control functions in connection with the operation of the elevator drive motor.

The electrical controls for an elevator system, particularly of the automatic type, are quite complicated. Because the invention relates primarily to the mechanism for correcting the creepage in the cables and improved means for controlling the elevator motor according to signals derived from the elevator motor, only those portions of the complete circuit which are directly related to the motor control are illustrated in the drawings. The circuits having to do with floor selection, registering of calls, operation of the elevator doors, and many other features have been omitted from these drawings.

Referring now to Figure IX, which illustrates schematically the circuits associated with the mechanism schematically illustrated in Figure I, the elevator driving motor 6, shown near the bottom of the drawing, is connected through leads 100 and 101 to a direct-current generator 102 which is driven at a constant speed by an alternating current motor 103.

The elevator drive motor 6 has its field coil 104 connected directly to direct current supply leads 105 and 106. While shown as directly connected, it is understood that control devices and safety devices may be included in this circuit to modify the operation of the motor. The generator 102 has a field coil 107 which is also energized from the power leads 105 and 106 according to the direction and speed at which the drive motor 6 is to run. In this arrangement the generator 102 is driven at constant speed by the alternating current motor 103 and the voltage appearing between the leads 100 and 101, the output voltage of the generator, varies according to the current flow of the field coil 107. Since the current flow in the field coil 104 of the motor 6 is constant the speed of the motor 6 varies directly as the voltage applied to its armature through the leads 100 and 101.

The direction of rotation of the elevator motor 6 is controlled by circuits represented by a single-pole double-throw switch 108 which, when it is in the position shown, permits current to flow through a lead 109, an operating coil 110 and a lead 111 to energize an up-direction control relay 112 and which, when it is thrown to its other position, permits current to flow through a lead 113, an operating coil 114 and lead 115 to operate a down-direction control relay 116. The armatures of the relays 112 and 116 are preferably interlocked, as by a crosslink 117 cooperating with a fixed abutment 118, so that neither relay will operate unless the other is in its de-energized position.

The generator field coil 107 is energized for upward or downward car travel according to which one of the relays 112 or 116 is operated. Assuming that it is desired to move the car upwardly, the field coil 107 is energized by current flowing through a circuit which may be traced from the power lead 105 through a first contact 119 of the up relay 112, through a lead 120, the generator field coil 107, a lead 121, a second set of contacts 122 of the relay 112, a lead 123 and rheostat resistance 124 to the return power lead 106. If it is desired to operate the car in a down direction the direction control switch 108 is thrown to its other position to de-energize the up relay 112 and energize the down relay 116. The latter relay then closes its contacts 125 and 126 so that current may flow from the power lead 105, through the now closed contact 125, a jumper lead 127 to the lead 121, the generator field coil 107, the return lead 120 from the field coil 107, 20 the now closed contact 126, the lead 123 and the rheostat resistance 124. This circuit reverses the direction of current flow through the generator field coil 107 so as to reverse the direction of rotation of the elevator motor 6. In an actual control the up or down control relay 112 or 116 is not energized until the car is ready to move.

Because of certain dangers and risks from improper operation elevator control systems are equipped with numerous safety or protective devices all of which must be in operating order before the elevator can be operated in its regular manner. These protective devices have been grouped together and are indicated by the symbol labeled "Protective Devices" shown in the upper portion of Figure IX. When these devices are all in order a circuit may be traced from a first alternating current power lead 128 through the now closed contacts of the protective devices and a lead 129 to an operating coil 130 of a safety relay 131 and then through a lead 132 to a second or return power lead 133. When the relay 131 is energized it closes its normally open contacts 134, 135, 136, 137 and 138; and opens its normally closed contacts 139 and 140.

When the elevator car is standing at a floor, leveling switches and start control devices, represented by the symbol "Leveling and Start Control" in the upper right hand portion of the drawing, complete a circuit from the power lead 128 through a lead 141 and an operating coil 142 of an advance motor stopping relay 143 and leads 144 and 145. As long as this circuit is maintained with the advance motor stopping relay 143 energized contacts 146 and 147 are held open. When the car is ready to go a master switch 148 is closed and the start control releases the advance motor stopping relay 143 so that current flows from the power lead 128 through the now closed master switch 148 and contacts 147, a lead 149 and, for upward movement of the car, through a lead 150, contacts 151 of the up relay 112, contacts 135 of the protective relay 131 and an up-direction field 152 of the advance motor 16, and a lead 153 to the return lead 133. For downward movement the circuit is through lead 154 connected to the lead 149, contacts 155 of the down relay 116, contacts 136 and down field winding 156 of the advance motor 16, and then through a lead 157 to the return lead 133.

The advance motor 16 is a two-phase alternating-current motor employing a resistor-condenser circuit 158 connected between its input terminals so that both fields are energized whenever the motor is to run, the condenser furnishing the

phase shift required between the current flowing in the two fields. Thus when the current flows through the lead 150 and contacts 151 and 135 the field coil 152 carries line current and the field coil 156 carries quadrature current so that the motor rotates in the up-direction. When the second field coil 156 is directly energized the first field carries quadrature current and the motor rotates in the opposite direction. The 10 rotation of the advance motor 16 through its connection to the input shaft 15 of the differential gear carrier 22 rotates the rheostat assembly 9, schematically illustrated as a disk 159 and a series of contacts 160, so as to progressively short out portions of the rheostat resistance 124 and thus increase the current flow in the generator field coil 107 and thereby, through the action of the generator 102, increase the speed of the elevator drive motor 6.

As will be recalled from Figure I, the advance motor 16 also drives a floor selector carriage 10 which, as shown in Figure IX includes a bridging contactor 161 and a pair of spaced contacts 162 and 163. The bridging contactor 161 cooperates with a series of fixed contact points 164, 165, 166, 167, 168 and 169 representing various floors that are served by the elevator. The contacts 164 and 169, representing the terminal floors, are connected directly to the supply lead 123 30 while the intermediate contacts 165 to 168 inclusive are connected through car buttons 170, 171, 172 and 173 to the power lead 128. The car buttons are the type which latch in place and are released either when the car reaches a terminal floor or when it reverses before reaching a terminal floor.

The floor selector mechanism also includes another set of contacts 174 to 179 inclusive that cooperate with both the bridging contactor 161 and the spaced contactors 162 and 163.

When the advance motor 16 is started by closure of the contacts 147 of the advance motor stopping relay 143 a circuit is also completed from the then energized lead 149 through a branch lead 180, the contacts 146 of the relay 143, operating coil 181 of an advance motor relay 182 and a lead 183, the closed contacts 134 of the protective device relay 131 and a lead 184 connected to the return power lead 133. As long as this circuit is completed the advance motor control relay 182 holds its contacts 185, 186 and 187 open.

As the floor selecting mechanism, driven by the advance motor 16, reaches a floor contact for which one of the car buttons has been actuated a circuit is completed to stop the advance motor and cause it to center the selector mechanism carriage 10 with respect to the contacts representing that particular floor. The first circuit to be completed may be traced from the power line 128 through the depressed one of the car buttons 170 to 173 or the terminal contacts 164 or 169, the bridging contactor 161 and the leading one of the spaced contacts 162 and 163. If the car is proceeding upwardly the carriage is also proceeding upwardly so that the spaced contact 163 first meets the cooperating one of the contacts 174 to 179. Current then flows from the contact through a lead 183, now 60 closed contacts 189 of the up relay 112, a lead 190 and operating coil 191 of a stopping relay 192 and then through a lead 193 and a motor control contact 194 to the return lead 133. The motor control contact 194 is closed during such time as the rheostat assembly 9 calls for opera-

70

tion of the elevator motor 6. As soon as the stopping relay 192 is energized it closes its normally open contacts 195 to complete a circuit from the lead 144 of the advance motor stopping relay 143 through a lead 196 to the return lead 133. The relay 143 thereupon opens its contacts 146 and 147 thereby breaking the circuit from the power lead 128 to the advance motor 16. When energized the stopping relay 192 also closed its other set of normally open contacts 197 so that current may flow from the lead 190 energized through the floor selector, through the now closed contacts 197 and a lead 198 to the lead 149 feeding the advance motor 16. The advance motor is energized through this circuit until it drives the floor selector mechanism carriage 10 far enough so that the leading contact 163 breaks connection with the corresponding one of the contacts 174 to 179 inclusive.

The opening of the contacts 146 of the relay 143 de-energizes the advance motor control relay 182 so that it then closes its contacts 185 to 187 inclusive. The contacts 187 connected between lead 199 and 200 provide a bypass circuit from the supply lead 128 to the bridging contactor 161 so that the floor selector button may be released without removing power from the bridging contactor 161.

The contacts 185 and 186 electrically connect the spaced apart contacts 162 and 163 respectively to the advance motor control fields through lead 201 and 202. This latter circuit directly connecting the spaced apart contacts 162 and 163 to the advance motor 16 causes the advance motor to turn one way or the other to keep the spaced apart contacts 162 and 163 accurately one on each side of and each spaced from the fixed contact representing the floor at which the elevator is to stop.

As the elevator approaches the floor and the rheostat 9 returns to its center position, the contact 194 opens and the circuit for the stopping relay 192 is opened. The direct circuit to the advance motor is still maintained so that the motor controlled by contacts 162 and 163 actively resists any forces tending to drive the selector carriage away from its proper position.

As the elevator is approaching the selected floor, the leveling switches, through circuits not illustrated, take over the control of the elevator drive motor 6 so as to accurately level the car with the selected floor. The leveling control, as the car approaches, closes a normally open set of contacts 203 to condition a circuit from the supply lead 128 through a lead 204, rheostat operated contacts 30 or 31, leads 205 or 206, contacts 137 or 138, correction motor control fields 207 or 208, contacts 209 operated by the elevator motor brake, and the now closed leveling control contacts 203 connected to the return lead 133. The brake contacts 209 are arranged to be closed as long as the spring-set brake mechanism 7 (Figure 1) is de-energized and the brake is applied to the motor shaft 5. Therefore this circuit cannot be completed as long as the elevator motor can move.

In the event that slippage of the cable has occurred so that the rheostat assembly 9 does not return exactly to center position, one or the other of the cam actuated contacts 30 or 31 remains closed and the correction motor 32 is energized so that it drives the differential input shaft 20 and slips the clutch 21 until the opening of the closed one of the contacts 30 or 31 indicates that

the rheostat has been returned to its center position.

The correction motor 32 is preferably a two phase motor and includes a condenser-resistor circuit 210 to supply the quadrature current to that one of the fields 207 or 208 not directly energized through the cam operated contacts 30 or 31. It will be noted that the correction motor 32 can be operated only at such time as the elevator motor 6 is stopped and the leveling control indicates that the car is level with a floor.

This latter condition is important because the elevator may be stopped between floors in response to an emergency signal and the brake applied so that the contacts 209 are closed but with the floor selector mechanism out of register with any floor and the rheostat in position to call for high speed. Such an emergency stop occurs whenever any one of the protective devices is operated so that the protective relay 131 is released. Release of this relay opens the contacts 135 and 136 of the circuits to the advance motor 16 and the contacts 137 and 138 controlling the correction motor 32 so that neither one of these motors may operate in its normal manner. The release of the protective relay 131 also closes its normally closed contacts 139 and 140 so that current may flow from the power lead 128 through the lead 204, the closed one of the cam actuated contacts 30 or 31, leads 205 or 206 and the now closed contacts 139 or 140 to the advance motor 16 which thereupon operates independently of any control of the floor selecting mechanism 8 and runs in the direction required to bring the rheostat assembly 9 back to its mid or zero speed position with the contacts 30 and 31 both open. This action of the advance motor synchronizes the position of the floor selecting mechanism carriage 10 and the elevator car 1 and thus eliminates the difference in position which normally occurs because of the lag of the elevator car position behind the corresponding floor selector carriage position. Auxiliary circuits (not shown) are provided so that an attendant may run the elevator at slow speed with the protective relay 131 de-energized to bring the elevator car to a floor. The circuit including the cam operated contacts 30 or 31 is maintained so that the advance motor 16 responds to any movement of the rheostat assembly 9 and rotates in a direction so as to keep the rheostat at its center position. Such rotation drives the floor selector carriage 10 at a speed and in a direction to keep it in step with the car. This type of control following an emergency stop is necessary because the elevator car may, for example, stop between the 4th and 5th floors while the floor selector mechanism may then be located between the contacts representing the 2nd to 4th or 5th to 7th floors depending upon the direction of travel and the lag required between the car and selector mechanism positions for normal operation. By causing the advance motor 16 to return the rheostat assembly to zero following an emergency stop the selector mechanism is automatically properly positioned and is ready for regular operation without any further synchronizing operations.

In this control system the correction motor 32 is energized only in the event that the elevator car is stopped level with a floor, as indicated by the leveling controls, at the same time that the elevator motor is de-energized and the brake applied. Under these conditions the correction motor circuit is completed and it operates through

the differential to center the rheostat assembly.

Figure X illustrates the electric circuits which may be used in connection with the elevator system shown in Figure II. As shown in Figure X the elevator drive motor 39 has its armature electrically connected through heavy leads 211 and 212 to a generator armature 213. The generator is driven at constant speed by an alternating current motor 214. A field winding 215 of the elevator motor 39 is continually energized from direct current power leads 216 and 217 by current flowing from the lead 216 through a branch lead 218, the field winding 215 and a second lead 219 connected to the power lead return 217. Protective devices may be included in this circuit to protect the elevator system and its passengers in the event that this field circuit should fail and control of the elevator be lost.

The generator includes a generator field winding 220 which is supplied with the electric current from the power leads 216 and 217. The current for the generator field is controlled according to the desired speed of operation of the elevator and is reversed to reverse the direction of operation. The circuit for supplying field current to the generator field 220 may be traced from the power supply lead 216 through a lead 221, contacts 222 of an "up" relay 223, and a lead 224 connected to the generator field 220. From the field 220 the current flows through a lead 225, contacts 226 of the relay 223, a lead 227, and part or all of a resistance 228 of the rheostat assembly 46 connected to the return lead 217. When it is desired to increase the speed of the elevator motor 39 the current flow through the generator field 220 is increased by shorting out successively larger portions of the rheostat resistance 228. The rheostat assembly 46 is shown as comprising a plurality of points or contacts 229 that are connected to the rheostat resistance 228 and which are connected together by a raised portion 230 of a rheostat disk 231 as the disk, which corresponds to the arm 47, rotates.

If it is desired to operate the elevator in a down direction the relay 223 is released and a "down" relay 232 is energized. When the relay 232 is energized it closes its contacts 233 and 234 so as to connect the generator field lead 224 to the lead 227 connected to the rheostat and to simultaneously connect the other generator field lead 225 to the supply voltage lead 221. This circuit connection reverses the flow of current in the generator field winding 220 so that the motor 39 operates in the reverse direction.

The "up" and "down" relays 223 and 232 have operating coils 235 and 236 that are selectively energized through leads 237 and 238 from a single-pole double-throw switch 239 connected to the supply lead 216. The single-pole double-throw switch 239 is a simplified representation of conventional up and down control circuits.

The control circuits in this embodiment are substantially the same as those shown in Figure IX. As shown in this figure the protective devices associated with the control circuits for the elevator are grouped together and indicated by the symbol marked "Protective Devices." When everything is in order for operation the "Protective Devices" complete a circuit from a first control power lead 240, through a lead 241, an operating coil 242 of a protective relay 243, and through a lead 244 to a return power lead 245.

The floor selecting mechanism, shown in the upper left hand portion of Figure X, includes

a bridging contact 246 and a pair of spaced contacts 247 and 248 that are carried on the carriage 44 illustrated schematically in Figure II. A plurality of car buttons 249 are arranged to control circuits from the power lead 240 to a series of contacts 250 to 255 inclusive that cooperate with the bridging contactor 246. There are no car buttons corresponding to the terminal floor contacts 250 and 255 since the car must

stop at these floors regardless if there is a car call for that floor or not. The car buttons 249 are of the latching type that remain closed until the car reaches a terminal floor or reverses. The bridging contactor 246 serves to connect the contacts 250 to 255 selectively to a second series of contacts 256 to 261 inclusive that cooperate with the spaced contacts 247 and 248. These car buttons, contacts, the circuits therethrough, the bridging contactor 246, and the spaced contacts 247 and 248 of the movable carriage are employed in the stopping circuits for the advance motor 41.

When everything is ready and the elevator is to move to another floor a master switch 262 is closed to complete a circuit from the supply lead 240 through normally closed contacts 263 of an advance motor stopping relay 264, a lead 265 to contacts 266 of the "down" relay 232 and to contacts 267 of the "up" relay 223. If it is desired that the car move upwardly the control circuits would have closed the single-pole double-throw switch 239 to energize the "up" relay 223 so that the contacts 267 will be closed. Also, since the protective devices are in order, the protective relay 243 will be energized and its contacts 268 and 269 will be closed while its contacts 270 and 271 are open. Thus, for movement in the up direction, the circuit from the master switch 262 is completed through the contacts 267 of the "up" relay 223, contacts 268 of the protective devices and a first field winding 269 of the advance motor 41 the other lead of which is connected to the return lead 245. Quadrature current for a second phase winding 273 of the advance motor 41 is supplied through a condenser resistor circuit 274.

If it is desired to run the elevator in the down direction the circuit closes and the single-pole double-throw switch is thrown to its lower position to energize the "down" relay 232. This relay when energized closes its contacts 266 so that a circuit is completed from the master switch 262, through the contact 266, the contacts 269 of the protective relay, and the second field winding 273 of the advance motor. When running in the down direction the resistor condenser circuit 274 supplies quadrature current for the first field winding 272 of the advance motor 41.

The master switch 262 is operated through circuits, not shown, when the leveling and start control is actuated and completes a circuit from the power lead 240, through operating coil 275 of the advanced motor stopping relay 264, and lead 276 to the start control.

This control, through an operating rod 277, also opens a set of contacts 278 included in the electrical circuit controlling the electrically actuated clutch 49. This circuit may be traced from the power lead 240, through a lead 279, the operation coil 69 of the clutch 49, a lead 280, and contacts 281 of the elevator brake to the return lead 245. The contacts 281, in parallel with the leveling control contacts 278, are closed whenever the elevator motor brake is electrically energized so that the elevator is in condition to run. Thus the clutch coil 69 is energized at all time that

the elevator is in condition to run as well as when the brake is set but the car is not level with a floor. The only time that both contacts 278 and 281 are simultaneously opened is when the car is leveled with a floor so that the contacts 278 are open and the brake is set so that the contacts 281 are opened.

When the start control is operated to start the elevator it releases the advance motor stopping relay 264 to close its normally closed contacts 263 and a second set of normally closed contacts 282 so that current may flow through an operating coil 263 of an advance motor relay 264, through contacts 285 of the protective relay 263, and back to the power lead 265. The relay 264, when energized, opens its contacts 286, 287 and 288.

The sequence of operations as the advance motor drives the selector carriage to the bank of contacts representing a selected floor may be followed and the control for the advance motor may be traced from the floor selecting mechanism through the various circuits and relays to the advance motor 41. Suppose the advance motor to be running to raise the carriage 44 of Figure II and that the car button 249 cooperating with the contact 253 to be the next stop. As the carriage approaches, the bridging contactor 246 interconnects the leads 253 and 259 so that current may flow to the upper spaced contact 297, through a lead 289, now closed contacts 290 of the "up" relay 223, lead 291, operating coil 292 of a stopping relay 293, and a contact 294 forming part of the rheostat assembly and which is closed during such time that the rheostat calls for rotation of the elevator motor. As soon as this circuit is completed the stopping relay 293 closes its contacts 295 to complete a circuit to energize the relay 264 and thus open the contacts 282 and 263. This interrupts the flow of current directly from the power lead 246 to the advance motor 41. The advance motor, however, is still energized through the spaced contact 247, leads 289 and 291, contacts 296 of the relay 293, and a lead 297 connected to the advance motor lead 255. When the carriage moves far enough so that the contact 259 enters the space between the spaced contacts 247 and 248 the circuit to the advance motor 41 and the relay 264 is interrupted so that this relay opens and the advance motor stops. The operation of the stopping relay 293, through circuits not shown, also operated the leveling control to re-energize the operating coil 219 of the relay 264 so that this relay is held energized when the relay 293 is released.

The opening of the contacts 282 of the relay 264 de-energized the relay 264 so that it closes its contact 288 to supply power through leads 298 and 299 to the bridging contactor 246 and also to connect the spaced apart contacts 247 and 248 through its contacts 286 and 287 to leads 300 and 301 leading through the protective relay contacts 268 and 269 to the advance motor 41. This last circuit energizes the advance motor directly should the carriage of the floor selecting mechanism move such that either of the contacts 247 or 248 touch the intermediate fixed contact. Thus the advance motor holds the carriage centered with respect to the floor contacts. If the elevator is moving in the opposite direction contacts 302 of the "down" relay 232 are closed rather than the contacts 296 of the "up" relay and the lower spaced contact 286 first meets the fixed contact 259 while the remainder of the circuit operates in the same manner.

If one of the protective devices or the operator should call for an emergency stop the elevator

motor generator field circuit is immediately opened, the protective relay 243 is released, and the brake is set on the elevator motor. At such time the direct circuits to the advance motor 41 are also broken at contacts 288 and 269 while alternate circuits through protective relay contacts 270 and 271 and one or the other of cam actuated switches 303 and 304 is completed. The switches 303 and 304 are actuated by cams on the rheostat shaft 48 and are arranged so that one or other of the switches is closed as long as the rheostat is not in its neutral position. The advance motor therefore runs in a direction so as to turn the rheostat shaft 48 back to its neutral position and in so doing drives the carriage 44 (Figure II) including the bridging contactor 246 and spaced contacts 247 and 248 to the position corresponding to the stopped position of the elevator car. Since the leveling devices were not actuated, a car not stopping at a floor, the circuit to the electromagnetic clutch 49 is not opened.

This circuit and the differential arrangement illustrated in Figure II, in a simple fashion, provides accurate rheostat operation for the speed control of an elevator motor during normal operation in running between and stopping at floors as well as under abnormal conditions when an emergency stop has been made between floors.

A slipping clutch cooperating with correcting devices may be applied to other types of elevator controls in addition to the type just described.

As shown in Figure XI, a slippable friction clutch 335 is interposed between an armature shaft 306 of an elevator drive motor 307 and a shaft 308 which is connected through gearing 309 to drive a floor finding motor control mechanism 310. A drive pulley 311 on the elevator motor shaft 306 carries a cable 312 from which an elevator car 313 and a counterweight 314 are suspended. A correction motor 315 is connected through gearing 316 to the shaft 308 extending between the clutch 335 and the floor finding gear 309.

In this system the floor finding mechanism 310 includes a carriage 317 that cooperates with contacts 318 to find the floors at which the car is to stop. This floor selecting mechanism is of a conventional type that is usually driven by a tape or cable attached to the elevator car and not subject to creepage as are the car supporting cables. The floor finding mechanism controls the associated circuits and includes contact arrangements arranged so that the elevator motor is accelerated and decelerated according to a pre-determined schedule as the floor finding carriage approaches a position corresponding to the selected floor.

When the car is within a few feet of the floor at which it is to stop, leveling controls including switches and actuators mounted in the car and in the hatchway take over the final control of the motor to level the car at the selected floor. After the car has stopped at the floor a circuit illustrated in Figure XII is brought into play to energize the correction motor 315 which then drives the shaft 308 and slips the clutch 335 until the floor finding mechanism carriage 317 is accurately centered on the contacts representing the selected floor. The correction motor, by slipping the clutch 335, synchronizes the position of the floor finding mechanism with that of the elevator car each time the car stops at a floor and thus makes it unnecessary to provide a separate slip-free drive from the elevator car to the floor finding mechanism.

The correction motor is continually mechani-

cally connected to the shaft 308 and is driven by that shaft as the elevator is operated. However, the friction drag of the motor 315 is not enough to slip the clutch 305 and interfere with the operation of the mechanism during travel between floors.

Figure XII illustrates those portions of the elevator control circuit which relate to the correction of position or synchronization of the floor finding mechanism with that of the car. In this circuit the elevator motor 307 is shown as being driven by power and signal circuits 319. The elevator car 313 includes leveling switches 320, connected through a suspended cable 321 to the control circuits 319, cooperating with inductor vanes or with actuators 322 spaced according to floors along the path of the elevator car. The floor selecting mechanism or floor finding mechanism includes along with other selector circuits a series of contacts 323 that are continually energized through a lead 324 and that cooperate with a pair of spaced apart contacts 325 and 326. These spaced apart contacts 325 and 326 are carried on the moving carriage 317 of the floor selecting mechanism and cooperate with the series of fixed contacts 323 representing the various floors. As long as the elevator is moving or stopped between floors the control circuit energizes a coil 321 of a relay 328 by current flowing through leads 329. When the relay is energized it opens its contacts 330 and 331 which are connected between the spaced apart contacts 325 and 326 of the floor finding mechanism and field coils 332 and 333 of the correction motor 315. If the elevator car is moving or stopped between floors, as may happen when an emergency stop is made, the relay is energized and the circuits to the correction motor 315 are open at the contacts 330 and 331.

When the elevator car is standing at a floor and the leveling control circuits indicate that the car is level with the floor the relay 328 is de-energized its contacts 330 and 331 are closed so that a circuit for the correction motor 315 may be completed from a supply lead 334 through the lead 324, through one of the contacts 323 to the spaced apart contact 325 in the event that the floor selecting mechanism is positioned slightly below its correct position or to the contact 326 in the event that the floor selecting carriage is too high. Assuming that the carriage is below its correct position current flows from the lead 324 through the contact 325, relay contacts 330, and the first field winding 332 of the correction motor to a return lead 335. Current also flows through a resistor-condenser circuit 336 to the second field coil 333 of the motor 315.

When the correction motor is energized it drives the shaft 308 and slips the clutch 305 until the floor selecting carriage is driven upwardly and the spaced apart contact 325 leaves the adjacent one of the fixed contacts 323. As soon as the circuit is broken the friction of the clutch 305 and the correction motor 315 causes the motor to stop quickly. In the event that the carriage is too high current flows from the leads 334 and 324, through the lower one of the spaced apart contacts 326 and through the relay contacts 331 and directly to the field coil 333 of the correction motor. This current flow in combination with quadrature current flowing through the condenser-resistor circuit 336 to the field coil 332 causes the correction motor 315 to drive the carriage downwardly until the spaced apart contacts 325 and 326 are on opposite sides of and out of con-

tact with the adjacent one of the fixed contacts 323.

The spaced apart contacts 325 and 326 each extend nearly but less than half of the distance between adjacent ones of the fixed contacts 323 representing the various floors served by the elevator. While the only lack of synchronism that may appear between the position of the elevator car and the position of the floor finder carriage occurs because of creepage or slippage of the elevator cable 312 on the pulley 311 the probable error in carriage position to be corrected by the correction motor 315 is a small percentage of the distance between the contacts 323. Therefore, it is improbable that the correction motor would drive the carriage to the wrong one of contacts 323 and thus introduce an error of one or more floors into the floor finding equipment. Should such an error occur it may be corrected by running the elevator to one or the other of the terminal floors depending upon the direction of the error.

In this arrangement the correction motor 315, which may be a slow speed induction motor, in combination with the slippable clutch makes it possible to eliminate the separate tape or cable drive ordinarily used with full control floor finding mechanisms.

Various modifications in the control circuits and in the details of the structure of the clutches of the correction device may be made without departing from the scope of the invention.

Having described the invention, I claim:

1. In an elevator control, in combination, an elevator car that serves a plurality of floors, an electric elevator drive motor, a variable voltage generator electrically connected to the motor for driving the motor, said generator having a control field, a rheostat connected to control the flow of current in the control field, a floor selector mechanism, a reversible constant speed motor for driving the floor selector mechanism, a differential gear mechanism having three elements which are operatively connected one to the constant speed motor, one to the elevator drive motor and one to the rheostat, a friction clutch interposed in one of the connections to the differential gear mechanism, and means for slipping the clutch to center the rheostat when the car is at rest at a floor.

2. In an elevator control, in combination, an elevator car that serves a plurality of floors, an electric elevator drive motor, a variable voltage generator electrically connected to the motor for driving the motor, said generator having a control field, a rheostat connected to control the current flow in the control field, a floor selector mechanism, a reversible constant speed motor for driving the floor selector mechanism, a differential gear mechanism having a first element connected to the constant speed motor, a drive connection from a second element of the differential gear to the rheostat, a friction clutch connected to the elevator drive motor, a connection from the friction clutch to the third element of the differential, and means including a motor operatively connected to the third element of the differential for slipping the clutch to center the rheostat when the elevator car is at rest at a floor.

3. In an elevator control, in combination, an electric drive motor for hoisting an elevator car, a variable voltage generator electrically connected to the motor for driving the motor, a rheostat connected in series with the generator field

for controlling its generated voltage, a floor selector mechanism adjacent the drive motor, a constant speed reversible motor connected to the floor selector mechanism for driving the selector mechanism, an electrical control system responsive to an operator's signals connected to the constant speed motor for driving the motor to position the selector mechanism in response to the signals, a differential gear mechanism having a pair of input connections and an output connection, one of said input connections being connected to the constant speed motor and the other of said inputs being connected to the elevator drive motor, a clutch having one portion connected to the output of the differential and another portion connected to the rheostat, means for releasing said clutch when the motors are at rest with the car at a floor, and means for centering the rheostat when the clutch is released.

4. In an elevator control system, in combination, an electric elevator drive motor, an elevator car, a friction drive between the elevator motor and the car, an elevator control mechanism having a part that moves according to movement of the car, a mechanical drive system from the elevator drive motor to the control mechanism part, a friction clutch included in said mechanical drive system, a second motor operatively connected to said drive system intermediate the clutch and the control mechanism, first signal means for indicating the condition of level of the car with respect to a floor served thereby, second signal means for indicating the position of the movable control mechanism part, and means responsive to said first and second signal means for energizing the second motor while the elevator motor is at rest to drive said control mechanism part to a position corresponding to the position of the car, thereby slipping the friction clutch in an amount to correct for the creepage in the friction drive between the elevator motor and the car.

5. In an elevator control system, in combination, an electric elevator drive motor, an elevator car, a friction drive between the elevator motor and the car, an elevator control mechanism having a part that is to be maintained in a predetermined relation to the position of the car, a mechanical drive system from the elevator drive motor to the control mechanism part, a friction clutch included in said drive system, a low speed synchronous motor geared to the drive system intermediate the friction clutch and the control mechanism part, signal means on the elevator car cooperating with said control mechanism for controlling the drive motor to stop the car level with a floor, said signal means also cooperating with the control mechanism to energize said low speed motor when the car is at rest to slip the clutch and synchronize the control mechanism with the elevator car position.

6. In an elevator control system, in combination, an electric elevator drive motor, an elevator car, a variable voltage generator for driving the motor, a contactor mechanism for controlling the generator, a friction drive from the drive motor to the car, an elevator control mechanism having a part that moves according to the desired movement of the car, a reversible constant speed motor for moving said control mechanism part, a differential having an input shaft driven by said constant speed motor, a friction clutch

having a first part driven by said elevator motor and a second part connected to said differential, said contactor mechanism being operatively connected to the third element of the differential, a slow speed reversible motor connected to the second part of said friction clutch, and circuit means for energizing the slow speed motor to center said contactor mechanism when the elevator car is at rest at a floor served thereby.

5 7. In an elevator control, in combination, an elevator car that serves a plurality of floors, an electric elevator drive motor equipped with a traction drive for driving said car, rotatable control means adapted to select the direction of rotation of said motor and control its speed, a floor selector mechanism comprising a plurality of fixed contacts and a movable carriage cooperating with the contacts, a reversible constant speed motor driving said carriage according to demands 10 for elevator service, a differential gear having three elements connected respectively to constant speed motor, the elevator drive motor, and the rotatable control means, a clutch in one of said differential gear connections, and means for slipping the clutch when the elevator car is at rest 15 at a floor to center said control means, whereby the effect of slippage in the traction drive is corrected.

20 8. In an elevator control, in combination, an elevator car that serves a plurality of floors, an electric elevator motor equipped with a traction drive for driving said car, floor selecting and motor control means, gearing including a clutch 25 operatively connecting the elevator motor to the floor selecting control means, and means operative when the elevator is at rest for slipping the clutch in an amount proportional to the accumulated slippage of the traction drive since the last previous correction.

30 9. In an elevator control, in combination, an elevator car that serves a plurality of floors, an electric elevator motor equipped with a traction drive for driving the elevator car, floor selecting means having a member that is moved to positions corresponding to the floors to be served as 35 the car is driven to such floors, gearing operatively connecting said elevator motor and the member of said floor selector, a clutch included in said gearing, means for indicating when the car is leveled with a floor, and means responsive to the leveling means and the floor selector means 40 adapted to slip the clutch to correct for slippage of the traction drive.

45 10. In an elevator control, in combination, an elevator car that serves a plurality of floors, an electric elevator motor equipped with a traction drive for supporting and moving the elevator car, an elevator control system, a mechanical connection from the elevator motor to the control system for continuously indicating the instantaneous position of the elevator car, other means for indicating when a car is leveled at a floor, a clutch included in said mechanical connection, and means responsive to said level indicating 50 means for slipping said clutch to correct said position indication for slippage of the traction drive.
